FEED-BACK CIRCUITS

John Richard Banker, Passaic, N. J., assignor to
 Allen B. Du Mont Laboratories, Inc., Passaic,
 N. J., a corporation of Delaware

Application April 24, 1943, Serial No. 484,497

14 Claims. (Cl. 179—171)

1

This invention relates to a device for obtaining an alternating current or voltage wave of a desired sort from a complex wave which contains one or more undesired waves as components. The invention will be described particularly by way of an illustrative example of how to remove an undesired sawtooth component of a given wave so as to result in an output signal of the desired square wave shape.

The invention may be understood from the description in connection with the accompanying drawing showing a diagram of connections.

In the drawing, reference character 1 indicates a vacuum tube having an input terminal 2 to which a complex wave such as the square wave 3 is fed and applied to the grid 4 that is provided with the grid leak 5. The cathode 6 of tube 1 is connected to the plate of tube 7, the cathode 8 of which is loaded with resistance 9.

A source of voltage 12 applies positive potential to the plate of tube 1 and negative potential to the resistance 9. A condenser 13 couples the cathode 6 to the grid of tube 14 that is provided with grid leak resistance 15. Positive potential is applied through load resistance 16 to the plate of tube 14 and the cathode of this tube is connected through resistance 17 to ground to bias this cathode.

A condenser 20 couples the plate of tube 14 to the grid of tube 21 which is provided with grid leak 22. Resistances 23 and 24 in series are connected between the positive side of the potential 12 and plate of tube 21 and a resistance 25 interposed between the cathode of this tube and ground. A lead 28 with condenser 30 couples a point between resistances 23 and 24 to one end of a resistance 29. The other end of this resistance 29 is connected to the negative side of source 12. The resistance 29 is provided with a sliding contact 31 which is connected by lead 32 to the grid of tube 7.

A condenser 23 is connected from lead 28 to ground on the side of condenser 30 opposite resistance 29, and the output lead 35 from the device is connected to the plate of tube 21.

The operation is as follows: When a signal such as the square wave 3 of voltage is applied to the grid 4, signals as shown at 38 and 39 are produced. The distortion of the horizontal portions of signal 38 is due to the time constant of the condenser 13 and resistance 15 combination and that of the amplified signal 39 is due to the time constant of condenser 20 and resistance 22.

Application of signal 39 to the grid of tube 21 causes a triangular wave to be produced as shown

5 at 40. This triangular wave is coupled by lead 28, condenser 30 and lead 32 to the grid of tube 7 in phase such as to add to the signal at 38 so that the sawtooth component is reduced in magnitude. In this way the coupling values of condensers 13 and 20 and resistances 15 and 22 can be greatly reduced in value while still maintaining good response for low frequency components of the original signal 3.

10 When the rapidly decreasing voltage of signal 39, represented by the first downwardly extending vertical line is fed to the grid of tube 21 the current through tube 21 suddenly decreases causing a sudden increase of potential on lead 35 as indicated by the first vertical line in signal 41. When the voltage of signal 39 is increasing, as indicated by the upwardly sloping line at the bottom of the signal 39, an increasing voltage is being applied to the grid of tube 21 tending to 15 cause the output voltage on lead 35 to decrease in phase opposition as is usual with amplifier tubes. However, the corresponding increase in voltage applied during the time represented by this upwardly sloping portion of signal 39 together with the very rapid rise of potential represented by the vertically extending portion that follows tend to cause the potential on lead 35 to decrease suddenly, but the voltage supplied by the condenser 33 discharging during this interval 20 of increasing potential on the grid of tube 21 maintains the potential on lead 35 constant during this time interval as represented by the first horizontal line in signal 41, and so on in a similar way while the device is in operation.

25 As shown by tests with an oscilloscope, when the first rapidly decreasing voltage of signal 39, represented by the first downwardly extending vertical line is fed to the grid of tube 21 the current through tube 21 suddenly decreases causing an increase of the potential at the junction of resistors 23 and 24 as shown by the first upward sloping line of wave form 40. This causes the condenser 33 to charge through the resistor 23, this prevents the potential on the lead 28 30 from rising as rapidly as the voltage on the lead 35.

35 When the voltage of signal 39 is increasing, as indicated by the upwardly sloping line at the bottom of the signal 39, an increasing voltage is being applied to the grid of tube 21 tending to cause the output voltage on lead 28 to decrease in phase opposition as is usual with amplifier tubes. The rate of this reduction is determined 40 by the rate of discharge through resistor 24. This discharge continues through the upwardly

sloping and vertical portions of wave form 39. With the downward slope of 39 the cycle repeats.

The square wave signal 41 on the output lead 35 from tube 21 is thus reproduced from the square wave of input signal 3 regardless of the effect of time constants of condensers 13 and 29 and resistances 15 and 22, since the distortion is balanced out by this circuit arrangement.

Sliding contact 31 on resistance 29 determines the amplitude of the triangular wave applied to the grid of tube 7 in a convenient way.

What is claimed is:

1. A feed back circuit, comprising a vacuum tube to the grid of which a signal is applied, a second vacuum tube having a resistance in its cathode circuit and having its plate connected to the cathode of said first tube, an amplifier coupled to the connection between said tubes, and a connection from the plate circuit of said amplifier to the grid of said second vacuum tube.

2. The device of claim 1, in which said last named connection includes a resistance.

3. The device of claim 1, in which said last named connection includes a resistance and a condenser in series.

4. The device of claim 1, in which said last named connection includes a variable resistance.

5. A feed back circuit, comprising a vacuum tube to the grid of which a signal is applied, a second vacuum tube having a resistance in its cathode circuit and its plate connected to the cathode of said first tube, an amplifier comprising a plurality of vacuum tubes coupled to the connection between said tubes, a connection from the plate circuit of said amplifier to the grid of said second vacuum tube, and an output lead connected to the plate of the last one of said plurality of vacuum tubes.

6. The device of claim 5, in which a resistance is located in the plate circuit of said amplifier and the output connection from said device is taken off between the plate of said amplifier and said last named resistance.

7. The device of claim 5, in which a resistance is located in the plate circuit of said amplifier and the output connection from said device is taken off between the plate of said amplifier and said last named resistance and a resistance is located between a source of potential and said last named resistance.

8. In a device of the character described, two vacuum tubes, the first one of which has its cath-

ode connected to the plate of the second one, an input circuit for said first tube, an amplifier having its control grid coupled to said plate and cathode, a second amplifier having its control grid coupled to the plate of said first named amplifier and having its plate coupled to the grid of said second named vacuum tube and an output circuit coupled to the plate of said second named amplifier.

9. The device of claim 8, in which said first tube has its plate connected directly to a source of positive potential.

10. The device of claim 8, in which said second tube has its cathode connected to a source of negative potential.

11. The device of claim 8, in which said first named amplifier has its cathode biased by a resistance.

12. The device of claim 8, in which said second named amplifier has a resistance between its plate and the grid of said second named amplifier.

13. The device of claim 8, in which said second named amplifier has a variable resistance between its plate and the grid of said second named amplifier.

14. The device of claim 8, in which said second named amplifier has a resistance between its plate and the grid of said second named amplifier and also has a resistance between said last named resistance and a source of positive potential.
